Des. 198,005
Patented Apr. 14, 1964

198,005

ALARM UNIT

Nathan Verger, Brooklyn, N.Y., assignor, by mesne assignments, to Pittsburgh Railways Company, Pittsburgh, Pa., a corporation of Pennsylvania

Filed June 28, 1962, Ser. No. 70,721

Term of patent 14 years

(Cl. D72—1)

FIG. 1

FIG. 2

FIG. 3

FIG. 4

FIG. 5

FIG. 6

FIG. 7

FIGURE 1 is a front elevational view of an alarm unit showing my new design;

FIGURE 2 is a rear elevational view thereof;

FIGURE 3 is a side elevational view of one side thereof shown on a smaller scale;

FIGURE 4 is a side elevational view of the opposing side thereof shown on the scale of FIGURE 3;

FIGURE 5 is a top plan view thereof shown on the scale of FIGURE 3;

FIGURE 6 is a bottom view thereof shown on the scale of FIGURE 3; and

FIGURE 7 is a perspective view thereof shown on an enlarged scale.

The dominant features of my design reside in the portions shown in full lines.

I claim:

The ornamental design for an alarm unit, substantially as shown and described.
